UNITED STATES PATENT OFFICE.

JOHN LEE, OF MANSFIELD, ASSIGNOR TO THE RUSSELL WRENCH AND NOVELTY COMPANY, OF RUSSELL, OHIO.

WRENCH.

SPECIFICATION forming part of Letters Patent No. 269,073, dated December 12, 1882.

Application filed October 18, 1882. (No model.)

To all whom it may concern:

Be it known that I, JOHN LEE, a citizen of the United States, residing at Mansfield, in the county of Richland and State of Ohio, 5 have invented a new and useful Wrench, of which the following is a specification, reference being had to the accompanying drawings.

Figure 1 is a side view of my improved wrench. Fig. 2 is a longitudinal sectional view of the same. Fig. 3 is a transverse sectional view on the line xx , Fig. 1, and Fig. 4 is a detail view of the adjusting-wedge.

The same letters refer to the same parts in all the figures.

15 This invention relates to that class of wrenches which are provided with a sliding jaw; and my invention consists in certain improved means for securing the said sliding jaw in any position to which it may be adjusted, as will 20 be hereinafter fully described, and particularly pointed out in the claims.

In the drawings hereto annexed, A represents the shank of my improved wrench, having a suitable handle, B, and provided at its 25 upper end with a fixed jaw, C.

D is the movable or sliding jaw, which is provided with a longitudinal opening, E, by which it is mounted upon the stem or shank A. The latter is provided on one side with 30 teeth or transverse corrugations F, engaging similar teeth, G, on one side of the opening E. At the opposite side of said opening E is a recess, H, formed in the body of the jaw D, and beveled, as shown, so as to accommodate 35 a wedge, I. The lower end of the jaw D has a screw-threaded opening, J, communicating with the recess H, and in which works a screw, K, provided at its lower end with a milled handle, L, by means of which it may be conveniently operated. The upper (or inner) end 40 of the screw K has an annular groove, M, to receive a pair of claws, N, formed at the lower end of the wedge I.

O is a coiled spring, arranged upon the screw 45 K, and interposed between the lower end of

jaw D and the handle L, which latter is provided with an annular recess, P, in which the said spring is partly accommodated. The spring O forms an elastic washer by which any slack caused by wear upon the screw K is 50 taken up, and rattling prevented. I also provide the handle L with a laterally-projecting thumb-piece, Q, forming a lever by which it may be readily operated, and which serves to prevent it from making more than about one-half revolution, which is sufficient to manipulate the wedge.

The operation of my invention will be readily understood. By manipulating the screw the wedge may be lowered, so as to permit 60 the jaw D to be moved upon the stem A, or forced upwardly, so as to clamp the jaw upon the stem and hold it securely in any position to which it may be adjusted. The teeth F and G engaging each other, as shown, absolutely 65 prevent the jaw from moving upon the stem when the wedge has been tightened.

This invention is applicable to all wrenches having sliding jaws without regard to the construction of said jaws.

I claim as my invention—

1. In a wrench, the combination, with the stem or shank having a fixed jaw, of the sliding jaw D, having beveled recess H, and screw K, provided with handle L and annular groove M, and the wedge I, having claws N, as and for the purpose set forth.

2. In a wrench, the combination, with the sliding jaw D, having beveled recess H, of the wedge I, having claws N, the screw K, having 80 annular groove M and handle L, provided with thumb-piece Q and recess P, and the spring O, as and for the purpose set forth.

In testimony that I claim the foregoing as my own I have hereto affixed my signature in 85 presence of two witnesses.

JOHN LEE.
